CLAIM

The ornamental design of a blank for stackable tray with locking lid, as shown and described.

DESCRIPTION

FIG. 1 is a perspective view of a blank for stackable tray with locking lid according to the inventive design;

FIG. 2 is an elevational view of one side, the other side being a mirror image thereof;

FIG. 3 is a top plan view thereof;

FIG. 4 is a front elevational view thereof;

FIG. 5 is a bottom plan view thereof; and,

FIG. 6 is a rear elevational view thereof.

The broken line showing on FIGS. 1 and 3 represent fold lines.
